(57) **CLAIM**

The ornamental design for a trouser vent, as shown and
described.

DESCRIPTION

FIG. 1. shows a perspective view of a trouser vent;

FIG. 2 shows a front view of the trouser vent;

FIG. 3 shows a rear view of the trouser vent;

FIG. 4 shows a right side view of the trouser vent;

FIG. 5 shows a left side view of the trouser vent; and,

FIG. 6 shows a top plan view of the trouser vent.

The shade lines in the Figures show contour and not surface
ornamentation.

1 Claim, 5 Drawing Sheets
